UNITED STATES PATENT OFFICE.

MARY P. M. CARR, OF ST. LOUIS, MISSOURI.

DESIGN FOR A CAR-STRAP.

SPECIFICATION forming part of Design No. 27,749, dated October 19, 1897.

Application filed May 26, 1897. Serial No. 638,311. Term of patent 14 years.

To all whom it may concern:

Be it known that I, MARY P. M. CARR, a citizen of the United States, residing at St. Louis, Missouri, have invented and produced 5 a new and original Design for Car-Straps, of which the following is a specification, reference being had to the accompanying drawing, forming a part thereof.

The leading feature of my design consists 10 in two annular or ring-like portions connected by a ligament.

The drawing represents an elevation of a car-strap, showing my design.

A designates the uppermost ring-like por- 15 tion, B the lowermost loop or ring-like por-

tion, and C the connecting ligament. This connecting portion extends in line with the centers of the two ring-like portions. The two rings and the ligament are shown as integral, without joint. 20

What I claim is—

The design for a car-strap, substantially as herein shown and described.

In testimony whereof I have signed this specification in the presence of two subscr- 25 ing witnesses.

MARY P. M. CARR.
